UNITED STATES PATENT OFFICE.

HERMAN J. HEGWER, OF OAKLAND, CALIFORNIA, ASSIGNOR TO HEGWER ILLUMINATED TARGET FINDER COMPANY, A CORPORATION OF ARIZONA TERRITORY.

ILLUMINATED TARGET-FINDER.

995,867.

Specification of Letters Patent. Patented June 20, 1911.

Application filed January 7, 1910. Serial No. 536,939.

To all whom it may concern:

Be it known that I, HERMAN J. HEGWER, a citizen of the United States, residing at Oakland, in the county of Alameda and 5 State of California, have invented certain new and useful Improvements in Illuminated Target-Finders, of which the following is a specification.

This invention relates to target illuminating devices for guns, revolvers, and the like, and the principal object of the same is to provide an illuminating device that may be readily controlled by the user of the firearm so that a ray of light may be projected from 10 the firearm to illuminate the target, the illuminating device being so arranged that its light ray will be projected parallel with the barrel of the firearm thereby permitting the firearm to be centered on the target without 15 the necessity of the user employing the end sight of the barrel.

In carrying out the objects of the invention generally stated above it will be understood, of course, that the essential features 25 thereof, are necessarily susceptible of changes in details and structural arrangements, one preferred and practical embodiment of which is shown in the accompanying drawings, wherein:

30 Figure 1 is a view in side elevation of a revolver equipped with the improved target illuminator. Fig. 2 is an end view thereof, the handle and trigger mechanism being omitted. Fig. 3 is a view in side elevation 35 of the illuminator, the casing thereof being shown in section. Fig. 4 is a detail view in side elevation of the circuit closer for the illuminator. Fig. 5 is a diagrammatic view showing the manner of projecting the light 40 rays from the illuminator.

In the accompanying drawings the improved illuminator has been shown attached to the barrel 1 of a revolver, but it is to be understood, of course, that it is not limited 45 to use in connection with the revolver for it will be obvious that it may be employed in connection with all types of firearms and guns. Said illuminator comprises a cylindrical casing 2 whose ends are open and 50 which is provided with spring arms 3 adjacent each end that are adapted for firm but detachable engagement with said barrel 1 to suspend the casing from the underside of the barrel, and in the event of the illuminator 55 being used in connection with a revolver

that has its cylinder supported upon a shaft 4, the outer end of said shaft may project through the open rear end of the casing 2 as is shown in Fig. 1. A battery 5 is located in the rear end of casing 2 and has a circuit wire connection 6 with a block 7 carried by the stock of the revolver, said wire extending through said block and having its end projected above said post to provide a contact point 8. A concaved reflecting speculum 9 is mounted within the casing 2 in advance of the forward end of battery 5 and is provided with a central opening 10 through which the socket 11 of an incandescent lamp 12 projects, said socket having its 60 contact post 13 in circuit with the post 14 at the forward end of battery 5. The socket 11 has a circuit wire 15 extending therefrom that passes through a pendent guide 16 carried by casing 2 and its outer end portion passes through a block 17 carried by the undersurface of the free end of an outstanding spring arm 18 projecting from the stock of the revolver. The portion of wire 15 that passes through block 17 has its end 70 suspended therefrom to provide a contact point 19 that is normally held above contact point 8 of wire 6, but which may be brought into contact with point 8 to close the circuit through battery 5 and lamp 12 75 by pressure applied to the free end of supporting arm 18 and thereby cause the filament 20 of lamp 12 to glow. The outer end of casing 2 is externally threaded as indicated at 21 so that an internally threaded 80 lens collar 22 may be adjustably and detachably fitted thereover. Said collar 22 holds a double convex lens 23 in engagement with the outer end of the casing 2.

The filament 20 of lamp 12 may be of the 95 U-shaped shown and it will be seen that when the circuit is closed through the battery and lamp, the rays from the filament will be concentrated by the speculum 9 and cause them to be directed to the lens 23 and from the lens to converge from the lens to the focal point, as is diagrammatically illustrated in Figs. 3 and 5, and as further suggested by Fig. 5, the light from the illuminator will cause an inverted image to be 100 thrown on the target that is a reflection of the filament 20, said image being the center of the light and being very bright and surrounded by the usual spot light or halo.

The spring arms that attach the illuminator

nator to the casing 2 are in the form of clips that partially surround the said casing and their arms are so arranged that they may be readily snapped to engagement with 5 the barrel 1.

It will be understood, of course, that in place of the double convexed lens shown in the drawings, two concavo-convexed lenses may be employed. And also that the distance from the said filament and the mutual 10 center line of the lens is such as to exactly equal the focal distances of said lens. If the focal distance is shorter, said lens will be necessarily arranged closer to the lamp 15 12 to correspond; if the focal distance is greater the distance between the lamp and the lens is increased. To accomplish the necessary adjustment of the lens to compensate for such differences in the distances, 20 the lens collar 22 may be adjusted through the medium of its threaded connection with casing 2.

What I claim as my invention is:—

A target illuminator comprising a casing,

means carried by said casing for detachably 25 securing the same to the barrel of a gun, a lens adjustably mounted in the forward end of said casing, a concaved reflector in said casing, intermediate its ends, an incandescent lamp mounted in said reflector and 30 projecting beyond the same and located from said lens at such a distance as to produce an enlarged inverted image, a battery in the rear end of said casing, circuit wires connected to said lamp and battery, a spring 35 arm secured to the butt of said gun, a contact block at the free end of said spring arm, and a second block secured to said butt, said circuit wires being fastened to said blocks and projecting therefrom in order to 40 close the circuit when pressure is applied to ~~the~~ said spring arms.

In testimony whereof I affix my signature in presence of two witnesses.

HERMAN J. HEGWER.
